AIR CONDITIONING APPARATUS

Alfred Weiland, Philadelphia, Pa., assignor to
Baldwin-Southwark Corporation, a corporation
of Delaware

Application December 29, 1933, Serial No. 704,418

2 Claims. (Cl. 62—129)

This invention relates generally to air conditioning apparatus and more particularly to an improved self-contained air conditioning unit employing a compressor-condenser-evaporator circuit constructed and arranged in such a manner as to effectively permit cooling of a condenser by outside air while at the same time maintaining a pleasing appearance and compact arrangement of the unit together with a simple and effective arrangement for circulating room air over the evaporator.

Various arrangements have heretofore been suggested in an attempt to provide a compact self-contained air conditioning unit but the same have been deficient in many respects. Certain of these prior arrangements have utilized water-cooled condensers which require expensive pipe installations and other inconveniences, whereas my improved unit employs an air-cooled condenser so arranged with the other elements that minimum floor space is required although various features of my unit are equally applicable to water-cooled condenser units.

It is one object of my invention to provide an improved self-contained substantially portable unit so arranged in cooperation with a window or other suitable opening in a room wall that outside air may be effectively circulated over the condenser to cool the same, and room air may be effectively circulated over the evaporator, the compressor mechanism being so related to the condenser and evaporator that minimum floor space is required while at the same time highly efficient and simple air flow passages are obtained. In one specific aspect of the invention I provide a vertical unit with an air-cooled condenser so disposed in an upper portion thereof that the unit may be conveniently placed either against a wall, or in a corner of a room, adjacent a window through which outside air is conducted over the condenser, the evaporator being disposed so that room air may be effectively circulated thereover in a simple manner without structural or functional interference from the condenser equipment, this being specifically accomplished by having a fan on one side of the evaporator so as to circulate room air directly transversely of the unit whereby the air enters one side of the unit and discharges from another side thereof in substantially horizontal directions.

A further specific aspect of the invention includes a motor-compressor unit disposed in a lowermost compartment in vertical alignment 55 with condenser and evaporator compartments,

thereby providing a vertical unit which requires relatively small floor space and yet permits the condenser to be disposed at a very desirable location for simple and effective communication with the outside atmosphere such as through either the top or intermediate portion of a window while at the same time allowing an efficient location of the evaporator so as to to insure circulation of the cooled and dehumidified room air at the most effective elevation.

Other objects and advantages will be more apparent to those skilled in the art from the following description of the accompanying drawings in which:

Fig. 1 is a perspective of my improved unit located against the wall between two windows whereby outside air is admitted through one window and discharged through the other;

Fig. 2 is a perspective of the modified form of unit placed in a corner of the room adjacent one window which functions to admit and discharge condenser cooling air;

Fig. 3 is a vertical section taken substantially on the line 3—3 of Fig. 1;

Fig. 4 is a plan section through the top of Fig. 2;

Fig. 5 is a plan section of the Fig. 1 form of unit placed in a corner with a window in each wall whereby outside air may be effectively circulated through one window and over the condenser and thence to the outside through the other window.

In the particular embodiments of the invention which are disclosed herein merely for the purpose of illustrating certain specific forms among possible others that the invention might take, I have shown in Fig. 1 a vertical unit generally indicated at 1 placed against a room wall and preferably between two windows 2 and 3. As shown in Fig. 3, the unit has three vertically aligned compartments containing a motor-compressor unit 30, an evaporator 4 and condenser 5. The motor-compressor unit may be of any suitable type but is herein shown preferably as of the vertical axis, hermetically sealed piston and cylinder type suitably supported on a base 6. Any suitable framework generally indicated at 7 may be secured on base 6 to support the condenser and evaporator and air circulating means therefor. The compartments are preferably separated by partitions 8 and 9 and formed of sheet metal or wood as may be desired. The evaporator and condenser are preferably disposed to one side of their compartments, thereby providing fan compartments generally indicated at 10

and 11, wherein any suitable fans or blowers 12 and 13, herein specifically shown as of the propeller type, are disposed directly behind the condenser and evaporator. Hence room air will flow 5 inwardly through a suitably grilled inlet 14 in one side of the unit and be circulated over evaporator 4 and thence discharged through a suitably grilled outlet 15 in the opposite side. This outlet may be provided with either vertical or 10 horizontal louvers to deflect the air either laterally or upwardly as desired.

Outside cooling air for the condenser is supplied from the top of window 3 through a window 15 inlet duct 16 preferably but not necessarily of triangular shape in plan view as shown in Fig. 1. A filter 17 may be disposed within this duct. The inflowing cooling air is then circulated by fan 13 over condenser 5 and thence through an outlet 20 window duct 18 communicating with the outside air through the upper part of window 2. The condenser 5 is preferably set back slightly from the left side of the unit to provide a vertical air passage from the lower portion of the condenser to the relatively narrow duct 18.

25 A filter 19 may be interposed between the inlet 14 and fan 12 to filter the circulated room air. Also to take care of the condensate dripping from evaporator 4, well-known moisture eliminators 30 may be placed on the discharge side of the evaporator. If the evaporator has vertical fins, the condensate may drip downwardly to accumulate in the bottom of the evaporator compartment, thereby to be pumped or otherwise circulated up over the condenser 5 to assist in cooling the same, 35 or the condensate may be accumulated and periodically drained. If transverse fins are used, then the evaporator may be slightly inclined rearwardly so that condensate will flow rearwardly against the direction of air flow thereover, this condensate dripping down along the back of the evaporator to accumulate in the bottom of the evaporator compartment. The evaporator is specifically shown as having transverse fins with vertical coil pipes and is shown slightly inclined as 40 above mentioned. An additional advantage of this slightly inclined evaporator is that the cooled room air is discharged into the room in an initial upward direction.

From the foregoing disclosures, it is seen that 50 an extremely compact unit is provided in so far as requiring minimum floor space and at the same time the condenser is so disposed that it may effectively cooperate with the window openings to permit outside air to be efficiently circulated over 55 the condenser and discharged to the outside. It is also seen that the room air is circulated in a simple straight path from one side of the unit to the other and in such a direction as to cause circulation of room air in substantially a horizontal plane. The cabinet for the unit may be of any ornate or simple design such as may appeal to 60 individual aesthetic tastes without in any way impairing the mechanical aspects or utility of the unit.

65 In the modification of Fig. 2, the unit 20 has the same arrangement of elements as that shown in Fig. 3 except a single window is utilized for the admission and discharge of outside air to cool

the condenser. As shown in Fig. 4, the unit is disposed in a corner 21 of a room and is slightly spaced from one wall so as to permit room air to enter the inlet opening corresponding to opening 14 of Fig. 3. The condenser fan, however, is 5 shown as of the centrifugal type having a spiral casing 22 whose inlet opens directly into the fan chamber 23 and whose outlet communicates directly with one-half of the condenser. A vertical partition 24 extending throughout the vertical length of the condenser 25 permits outside air to be drawn inwardly through a window duct 26 and over one-half of the condenser and into the chamber 23, thence into the fan casing to be discharged over the other half of the condenser and 10 out through another portion 27 of the window duct. 15

In the modification of Fig. 5, the unit of Fig. 3 is disposed in a corner and is slightly spaced from one wall thereof to permit room air to enter 20 its inlet opening corresponding to 14 of Fig. 3. The arrangement is otherwise identical to Fig. 3 except that the inlet duct 16' communicates with a window 3' while the outlet duct 18' communicates with a window 2'. 25

From the foregoing disclosures of these modifications it is seen that they have the same structural and functional advantages as above pointed out for the preferred form shown in Figs. 1 and 3 while other advantages inherent in the unit will 30 be apparent to those skilled in the art.

It will of course be understood that various changes in details of construction and arrangement of parts may be made by those skilled in the art without departing from the spirit of the 35 invention as set forth in the appended claims.

I claim:

1. A self-contained air conditioning unit comprising, in combination, means forming two vertically aligned compartments containing respectively and at one side of said unit an air-cooled condenser and an evaporator; a motor-compressor mechanism arranged so that said compartments and mechanism are in relatively superimposed relation; and means including blowers disposed in the other side of said unit behind the condenser and evaporator for circulating outside air horizontally over said condenser and transversely thereof and thence back to the outside and for circulating room air over said evaporator. 40

2. A self-contained air conditioning unit comprising, in combination, means forming two vertically aligned compartments, an air-cooled condenser disposed in the upper one of said compartments and an evaporator disposed in the other compartment; a motor-compressor mechanism arranged so that said compartments and mechanism are in relatively superimposed relation; means for circulating outside air horizontally over said condenser and transversely thereof and thence back to the outside including window ducts leading from different sides of said condenser compartment to windows adjacent the same; and means for circulating room air over 55 said evaporator. 60

ALFRED WEILAND.
